UNITED STATES PATENT OFFICE.

JOHN L. KOLBE, OF CROOKSTON, MINNESOTA.

DUMP WAGON.

1,418,937.

Specification of Letters Patent. Patented June 6, 1922.

Application filed June 13, 1919. Serial No. 303,925.

To all whom it may concern:

Be it known that JOHN L. KOLBE, a citizen of the United States, residing at Crookston, in the county of Polk and State of Minnesota, has invented new and useful Improvements in a Dump Wagon, of which the following is a specification.

The object of the invention is to provide a dump body wagon suitable for farm use and adapted for the transportation of products and materials of various kinds requiring modifications in the methods of handling; and further to provide a device for the purpose indicated in which the plane or axes of the dumping movement may be modified to suit the conditions of use and the characteristics of the material constituting the contents of the body; and incidentally to provide an apparatus where either mechanical, horse or hand power may be employed in the operation of the mechanism necessary to the dumping movement of the body according to the conditions incidental to the use thereof.

With these and related objects in view as will appear from the following description of a preferred embodiment of the invention the same consists of a construction, combination and relation of parts which, however, are susceptible of modification as to forms and proportion within the scope of the appended claims without departing from the principles involved.

In the drawings:

Fig. 1 is a plan view of a vehicle embodying the invention.

Fig. 2 is a side view of the same, showing the depressible or dumping edge of the wagon body.

Fig. 3 is an end view showing the body in full lines in its normal and in dotted lines in its displaced or dumping position.

Fig. 4 is an end view showing the body in its dumping relation to the other parts in an elevated position as compared with that shown in Fig. 3.

Fig. 5 is a view similar to the Fig. 4 showing the body in an intermediate dumping position.

Fig. 6 is a detail view of one corner of the dumping body.

Fig. 7 is a similar view of one end of a frame wall to show the bearings for the body fulcrums which are interchangeable employed to secure the movement of the body

to its dumping positions at various elevations.

Fig. 8 is a detail sectional view of the end wall of the dumping body substantially in the plane of the main fulcrum pin as on the plane indicated by the line 8-8 of Fig. 6.

The wagon frame may be variously constructed to suit the purpose for which it is intended but should include the end walls 10 and 11 which may as in the construction illustrated form the front and rear walls of the vehicle bed and a side wall 12 connecting said end walls, the opposite side of the frame being open to permit of the movement of the dumping body which, as illustrated, embodies essentially the end walls 13, the side walls 14 and 15 and the bottom 16, the latter being slatted or composed of spaced bars if desired. The outlet or depressible side wall of the wagon body may be fitted with a movable tail gate 17 hinged as at 18 and normally held closed by latch 19 engaged with a catch 20 carried by the bottom of the body, said latch being operable by means of a rod 21 accessible to an attendant standing at one end of the structure when the wagon body, for example, is in its tilted or discharging position.

In its normal or carrying position the wagon body is supported by means of runners 24 bearing upon rests 23 consisting of bars disposed longitudinally of and close to the lower edges of the end walls 10 and 11 of the wagon frame, as shown in Fig. 7, said end walls of the body fitting between the rest bars to give stability to the structure.

Carried by the end walls of the wagon frame between which the tilting movement of the body is effected there is a plurality of bearings located at different locations and severally designated as 25, 26, 27 for the reception interchangeably of fulcrum pins or studs on the body to form the axes of movement of the latter as it is tilted from the normal to the dumping position, said bearings being arranged at different elevations and being formed of straps or brackets and being arranged preferably in different vertical planes as specifically indicated in Fig. 7. Fixed to the end walls of the wagon body are the fulcrum pins or studs 28 which are adapted for engagement with the bearings 25 and into which they naturally

drop or move as the body is rocked from the normal or carrying position indicated in full lines of Fig. 3 toward the position indicated in dotted lines of said figure. When in the 5 normal or carrying position said fulcrum pins or studs occupy seats 29.

Mounted on the discharge end of the body are the rods 30 fitted in suitable guides 31 and connected with bolts 32 which form fulcrum pins or studs when projected beyond the end edges of the side wall, the adjacent extremities of said rods 30 being connected to an operating lever 33 which when in the full line position indicated in Fig. 2 serves 10 to hold the bolts in their retracted or housed positions, which, when in the dotted line position *a* in said figure serves to project the bolts into positions where their terminals constituting the fulcrum pins or studs 15 will engage the bearings 26, and which when in the dotted line position *b* in said Fig. 2 will still further project said bolts to cause their terminals constituting the fulcrum pins or studs to engage the bearings 27. 20

25 Thus when the fulcrum pins or studs 32 are withdrawn or housed the tilting movement of the wagon body will be upon an axis determined by the engagement of the fulcrum pins or studs 28 in the bearings 25.

30 When the lever 33 is adjusted to the position indicated by dotted lines *a* of Fig. 2, the tilting movement of the body will be with reference to an axis determined by the engagement of the fulcrum pins or studs 32 35 with the bearings 26, whereas upon a full extension of the bolts 32, effected by the movement of the lever 33 to the dotted line position shown in Fig. 2 the tilting movement of the body will be with reference 40 to an axis determined by the engagement of the fulcrum pins or studs 32 with the bearings 27. Said bearings 25, 26, 27 being at different elevations, it is obvious, that the elevation of the discharge side or tail gate 45 of the body with reference to the plane of the wagon frame will be regulatable by the use of one or the other of the means described for determining the axes of dumping movement, to suit the conditions under which the 50 wagon may be operated or the character of the material which is being handled.

The means for effecting the tilting movement of the body consist of the tilting levers 34, fulcrumed as at 35 to the end walls of 55 the wagon frame and terminally having sliding connections with the dumping body. The body, for example, is provided with guides 36 and the levers with pins 37 for traversing the guides, there being means for swinging 60 said levers from the full line position A indicated in Fig. 3 to the dotted line position B in the same figure. Obviously the means for actuating the tilting levers may be variously modified, but as illustrated, consist 65 of cables 38 preferably connected with the

extremities of the levers as at 39, designed to give a substantially uniform leverage during the movement of said arms, and guide or direction rolls 40 around which the cables extend to the point of application of power 70 which may be either mechanical, horse or hand as may be desired. It is preferable as shown in the drawings to provide the cables with an intermediate traction loop 41 to which a team may be connected, and also to 75 use in connection therewith a drum 42 having a crank 43 so that when the use of horse-power is undesirable or impossible by reason of limited space, the tilting movement of the body may be effected by hand power, but it 80 will be understood that the drum or drums for this purpose may be located wherever it may be most convenient to the operator, taking into consideration the purpose for which the apparatus is designed, and as will 85 be understood, either at the ends of the frame or at the side thereof. The return of the body to its normal or carrying position may be effected either by hand power or otherwise, as by grasping the free edge of 90 the body or by attaching thereto a rope which may be manipulated from the ground at a point near the vehicle. Obviously after the body has been moved from the dumping position a short distance towards its normal 95 position its weight will return it to its position on the bed, such movement being controllable by tension on the operating cables 38 regulated by the operating drum. Rising from the end walls of the supporting frame 100 there are provided the uprights or standards 44 forming hitching posts which are commonly employed in connection with devices of this kind and which serve as means also for attachment of retaining ropes to extend 105 over the load contained by the body when there is a possibility of displacement of the latter in transit.

The invention having been described, what is claimed as new and useful is:

1. A dumping body wagon having a supporting frame provided with end walls, a tilting body mounted for movement between said walls, the frame being provided with rest bars and the body with runners for engagement with said rest bars, fulcrum pins or studs on the body adjacent extremities of the runners, open topped bearings on the end walls of the frame for the reception of said fulcrum pins or studs, and means for effecting the tilting movement of the body. 115

2. A dumping body wagon having a supporting frame provided with end walls, a tilting body mounted therebetween, said body being provided with end runners and the end walls of the frame with rest bars for supporting the same, fulcrum pins or studs projecting terminally from the body, open topped bearings carried by said end walls in position to receive said fulcrum pins 120

125

130

or studs, other bearings located upon said end walls above the plane of the first named bearings and extensible fulcrum pins or studs for engagement with the second named 5 bearings, and means for effecting the tilting movement of the body.

3. A dumping body wagon having a supporting frame and a tilting body mounted thereon, the body being provided with a 10 slotted guide on the upper edge at each end, tilting levers pivoted to the frame at intermediate points in the levers for swinging movement in planes parallel with the body,

the levers being provided at one extremity with pins slidably engaging the slots in the 15 guide, and cables terminally connected to the levers at the ends opposite said pins, the cables being trained over direction pulleys and united at the remaining ends to provide a point for the application of power 20 by which the levers may be rocked and the body swung thereby as herein shown and specified.

In testimony whereof he affixes his signature.

JOHN L. KOLBE.
